DESIGN FOR AN ELECTROSTATIC CONDENSER

Hans M. Peters, Astoria, N. Y., assignor to
Electro-Mechanical Research Inc., Brooklyn,
N. Y., a corporation of New York

Application August 10, 1935, Serial No. 58,071

Term of patent 7 years

To all whom it may concern:

Be it known that I, Hans M. Peters, a citizen
of the United States, residing at 26-80 30th St.,
Astoria, in the county of Queens and State of New
York, have invented a new, original, and ornamental
Design for an Electrostatic Condenser, of
which the following is a specification, reference
being had to the accompanying drawing, forming
part thereof.

In the drawing—

Fig. 1 is a perspective view of an electrostatic
condenser showing my new design.

Fig. 2 is a top plan view of Fig. 1.

Fig. 3 is a front elevational view of Fig. 2.

What I claim is:

The ornamental design for an electrostatic con-
denser, substantially as shown.

HANS M. PETERS.
